RAILWAY BRAKING APPARATUS

Herbert L. Bone, Pittsburgh, Pa., assignor to The
Union Switch & Signal Company, Swissvale,
Pa., a corporation of Pennsylvania

Application October 5, 1934, Serial No. 747,047

9 Claims. (Cl. 303—20)

My invention relates to railway braking apparatus, and particularly to braking apparatus of the type comprising wheel-engaging braking bars located beside a track rail, and movable toward and away from the rail into braking and non-braking positions. More particularly, my invention relates to apparatus of the type described wherein the braking bars are arranged to be moved to their braking positions by means of one or more fluid pressure operated motors, and to be restored to their non-braking positions by a suitable biasing means, such as gravity.

Specifically, my present invention relates to means for controlling the supply of fluid pressure to, and exhaust of fluid pressure from, the fluid pressure motor or motors of braking apparatus of the type described when the braking apparatus is to be utilized in connection with a duplex pressure fluid distribution system such as is disclosed and claimed in Letters Patent of the United States, No. 2,003,034, granted to me on May 28, 1935, and one object of my invention is to improve and simplify the control means disclosed in the said application.

Other objects of my invention will appear as the description proceeds.

I will describe several forms of apparatus embodying my invention, and will then point out the novel features thereof in claims.

In the accompanying drawings, Fig. 1 is a view, partly sectioned and partly diagrammatic, illustrating one form of apparatus embodying my invention. Figs. 2 and 3 are views, similar to Fig. 1, but showing modified forms of the apparatus illustrated in Fig. 1, which modified forms of apparatus also embody my invention. Fig. 4 is a fragmentary view showing another modified form of the apparatus illustrated in Fig. 1, and also embodying my invention.

Similar reference characters refer to similar parts in each of the several figures.

Referring first to Fig. 1, the reference character 1 designates one track rail of a stretch of railway track, which track rail, as here shown, is secured to a rail support 2 mounted on an adjacent pair of the usual crossties 3, only one crosstie 3 being visible in the drawings. Associated with the rail 1 is a car retarder comprising two braking bars A¹ and A² located on opposite sides of the rail. Each of these braking bars comprises, as usual, a brake beam 4 and a brake shoe 5.

The braking bars are arranged to be moved toward and away from the rail 1 by means of a lever 6 which is pivotally mounted at one end on a pivot pin 8 carried by the rail support 2, and a lever 7 which is pivotally mounted intermediate its ends on the pivot pin 8. The lever 6 is inclined upwardly and extends away from the rail 1 and is provided in its upper surface

with a groove 6^a which receives the braking bar A¹. The one end 7^a of the lever 7 is likewise inclined upwardly and extends away from the rail 1 at the opposite side of the rail from the lever 6, and the other end 7^b of the lever 7 is inclined downwardly and extends away from the rail 1 below the lever 6. The end 7^a of the lever 7 is provided in its upper surface with a groove 7^c, similar to the groove 6^a in the lever 6, which groove receives the braking bar A². The parts are so proportioned that if the outer or free ends of the levers 6 and 7 are moved apart, the braking bars will be moved toward the rail 1 into their effective or braking positions. When the braking bars occupy their braking positions, the brake shoes 5 will engage the opposite side faces of a car wheel traversing rail 1, and will retard the speed of the car. The center of gravity of the lever 6 and braking bar A¹ is considerably to the right of the pivot pin 8, so that this lever will normally tend to rotate in a clockwise direction about the pivot pin. Similarly, the center of gravity of the lever 7 and braking bar A² is to the left of the pivot pin 8, so that this lever will normally tend to rotate in a counter-clockwise direction about the pivot pin. It will be apparent, therefore, that when no force is applied to the free ends of the levers 6 and 7 to move them apart, the free ends of these levers will move toward each other, thereby moving the braking bars to their ineffective or non-braking positions in which they are shown in the drawings.

The levers 6 and 7 are arranged to be moved apart to move the braking bars to their braking positions by means of a fluid pressure motor M comprising a cylinder 9 containing a reciprocable piston 10 which drives a piston rod 11. The cylinder 9 is pivotally connected with the free end of the lever 6 by means of trunnions 12 formed on the side of the cylinder and extending through bifurcations 13 formed on the lever 6, while the piston rod 11 is connected at its free end with the free end 7^b of the lever 7 by means of an adjustable eye bolt 14 and a pivot pin 15. Fluid pressure may be admitted to the cylinder 9 between the upper end of the cylinder and the piston 10 through an opening 16 which is threaded to receive a pipe 16^a. When fluid pressure is admitted to the cylinder 9 through the pipe 16^a and opening 16, the piston 10 will be forced downwardly and the cylinder 9 upwardly, thereby separating the levers 6 and 7, and hence moving the braking bars toward their effective or braking positions, it being obvious that when the braking bars are moved to their braking positions, they will exert a braking force which is proportionate to the pressure of the fluid supplied to the cylinder 9.

It should be pointed out that while in the

drawings I have shown only one operating unit for the braking bars A¹ and A², in actual practice these braking bars are provided with a plurality of other similar operating units, disposed at spaced intervals along the bars, substantially as shown in Letters Patent of the United States, No. 1,927,201, granted to me on September 19, 1933, for Railway braking apparatus. It should also be pointed out that, as a general rule, the car retarder will consist not only of braking bars associated with one track rail, as shown in the drawings, but also of similar braking bars associated with the opposite rail as well, the length of the braking bars associated with both track rails being determined by the speed and the weight of the cars to be retarded, the lengths of the cars, the number of wheels on the cars, etc.

The supply of fluid pressure to cylinder 9 is controlled by three main air valves 16, 17 and 18, which main air valves are, in turn, controlled by three electro-pneumatic pilot valves V¹, V² and V³. The pilot valves V¹, V² and V³ are similar, and each comprises a valve stem 19 biased to an upper position by means of a spring 20, and provided with a winding 21 and an armature 22. When one of the valves V is energized, valve stem 19 of this valve moves downwardly against the bias exerted by the associated spring 20, and, under these conditions, an associated pipe 23 is connected with a pipe 24. When one of the valves V is deenergized, however, the associated pipe 23 is disconnected from pipe 24 and is connected with atmosphere through a port 25. The pipe 24 forms part of a high pressure distribution system, and is constantly supplied with fluid pressure, usually air, from a relatively high pressure source not shown in the drawings. It follows, therefore, that when one of the valves V is energized, the associated pipe 23 is supplied with fluid pressure from the high pressure system.

The main air valves 16, 17 and 18 are all located in the same valve body 26, and associated with each valve is a spring 27 which constantly biases the valve to an upper or closed position. Formed in the valve body 26 in axial alignment with the valve 16 is a cylinder 28 containing a reciprocable piston 29 which is operatively connected with the valve 16 by a valve stem 30. The upper end of the cylinder 28 is connected with the pipe 23 which is associated with valve V¹, and it will be apparent, therefore, that when valve V¹ is deenergized, so that the associated pipe 23 is connected with atmosphere, the spring 27 associated with valve 16 will hold this valve closed and piston 29 in its upper position, but that, when valve V¹ is energized, as shown in the drawings, the fluid pressure which is then supplied to the associated pipe 23 will force piston 29 to its lowermost position, thus opening valve 16. When valve 16 is opened, cylinder 9 of motor M is connected with atmosphere through pipe 16^a, a chamber 31 formed in valve body 26, a passageway 32, a chamber 33 formed in valve body 26, valve 16, a chamber 34 formed in valve body 26, and a port 35, but when this valve is closed, cylinder 9 is disconnected from atmosphere.

The valve body 26 is also formed with a second cylinder 36 containing a reciprocable piston 37 which is operatively connected with the valve 17 by means of a piston rod 38, and the upper side of which cylinder is connected to the pipe 23 associated with valve V². When valve V² is

energized, the fluid pressure which is then supplied to the associated pipe 23 forces piston 37 to its lowermost position, thereby opening valve 17, and under these conditions cylinder 9 of motor M becomes connected with a pipe 39 through pipe 16^a, chamber 31, valve 17, and a chamber 40 formed in valve body 26. Pipe 39 forms part of a low pressure distribution system, and is constantly supplied with fluid pressure, usually air, from a relatively low pressure source not shown in the drawings. It follows, therefore, that when valve V² is energized, fluid from the low pressure source will be supplied to cylinder 9. When valve V² is deenergized, however, the spring 27 associated with valve 17 moves valve 17 to its closed position and piston 37 to its upper position, thus disconnecting cylinder 9 from pipe 39, and hence from the low pressure source.

The valve body 26 is further formed with a third cylinder 41 containing a reciprocable piston 42 which is operatively connected with valve 18 by means of a piston rod 43. The cylinder 41 on the upper side of piston 42 is constantly connected with the pipe 23 associated with valve V³, and it will be apparent, therefore, that when valve V³ is energized, piston 42 will open valve 18. When valve 18 becomes opened, cylinder 9 becomes connected with pipe 24, and this cylinder is then supplied with fluid from the high pressure distribution system. When valve V³ is deenergized, however, spring 27 associated with valve 18 closes this valve which, in turn, disconnects cylinder 9 from the high pressure distribution system.

It follows from the foregoing that cylinder 9 will be connected with the high pressure source, the low pressure source, or with atmosphere, according as valves V³, V² or V¹ are energized.

The valves V are controlled in part by a plurality of pressure responsive devices, each designated by the reference character P with a distinguishing exponent. Referring to the pressure responsive device P¹⁵, for example, this device comprises a Bourdon tube 44 connected with the pipe 23 associated with valve V², and subjected to the pressure on the upper side of piston 37. The Bourdon tube 44 controls a contact 45—45^a which is closed at all times except when the pressure on the upper side of piston 37 is equal to or above the pressure at which valve 17 opens. The pressure responsive devices P^{20—30}, P^{70—80} and P^M are similar to the pressure responsive device P¹⁵, except that the Bourdon tube 44 of each of these devices is connected with the pipe 16^a which communicates with the cylinder 9 of motor M, thus subjecting these devices to the pressure of the fluid in the motor cylinder. The devices P^{20—30} and P^{70—80} are arranged to operate at different pressures as the pressure in cylinder 9 increases. For example, for all pressures below 20 pounds per square inch, contact 45—45^a of each of these devices is closed. If the pressure exceeds 20 pounds per square inch, contact 45—45^a of device P^{20—30} opens, and if the pressure exceeds 30 pounds per square inch, contact 45—45^b of device P^{70—80} closes. In similar manner, the device P^M is adjusted to open its contact 45—45^a at 70 pounds per square inch, and to close its contact 45—45^b at 30 pounds per square inch. Of course, these specific pressures are not essential, but are only mentioned for purposes of illustration.

The Bourdon tube 44 of device P^L is connected by means of a pipe 46 with a reservoir R, which

reservoir, in turn, is connected with the pipe 39 by means of a pipe 47. A restricted orifice 48 is provided in the pipe 47, and the function of this restricted orifice and of the reservoir R is to prevent rapid fluctuations which may occur in the low pressure distribution system, of which the pipe 39 forms a part, from being transmitted to the Bourdon tube 44 of the device P^L. The member 45 controlled by the tube 44 of device P^L is connected mechanically with the member 45 controlled by the tube 44 of device P^M by means of a link 45, and it will be seen, therefore, that the members 45 of the two devices P^M and P^L are constrained to move together, but that, these members oppose each other when fluid pressure is admitted to the associated Bourdon tubes. The contacts 45-45^a and 45-45^b controlled by Bourdon tube 44 of device P^M are so constructed that these contacts cannot become simultaneously closed, and the parts are so proportioned that contact 45-45^a of device P^M will close when the pressure in the low pressure system exceeds that in the motor cylinder 9 by five pounds per square inch or more, and that contact 45-45^b of device P^M will close when the pressure in the cylinder 9 of motor M exceeds that in the low pressure distribution system by five pounds per square inch or more.

The valves V are also controlled by a manually operable lever L, which, as here shown, is capable of assuming five positions, indicated by dotted lines in the drawings, and designated by the reference characters p¹ to p⁵, inclusive. The lever L controls a plurality of contacts, each designated by the reference character 50 with a distinguishing exponent corresponding to the position of the lever in which the corresponding contact is closed. For example, contact 50¹ is closed in the p¹ position of the lever, contact 50² in the p² position of the lever, etc.

Lever L will usually be located at a point remote from the braking apparatus, as in the control cabin of a classification yard car retarder system, and will be connected with the braking apparatus by means of line wires extending from the control cabin to the braking apparatus.

The pressure of the fluid in the low pressure system may be maintained at any suitable pressure, but for purposes of illustration, I will assume that this pressure is maintained at approximately 50 pounds per square inch. Likewise, the pressure of the fluid in the high pressure system may be maintained at any desired pressure, but for purposes of illustration, I will assume that this latter pressure is maintained at approximately 100 pounds per square inch.

As will be explained more fully hereinafter, fluid is at times vented from the motor M into the low pressure system, and in order to insure that all of the fluid in the low pressure system may be used, and also that the compressing of the fluid may be done most efficiently, it is preferable that the fluid for the high pressure system should be obtained by the use of a compressor which will draw fluid from the low pressure system and compress it to the pressure required for the high pressure system, instead of compressing the fluid directly from atmospheric pressure to the pressure required for the high pressure system.

As shown in the drawings, lever L occupies its p¹ or "off" position, which is the position which this lever normally occupies when no cars are to be retarded, and all of the contacts of lever L with the exception of contact 50¹ are therefore open. Valves V² and V³ are both deenergized.

Valve V¹, however, is energized over a circuit which passes from a suitable source of current here shown as a battery B, through wires 73, 64, 62 and 61, contact 50¹ of lever L, line wire 51, wire 52, winding 21 of valve V¹, wire 53, contact 45-45^a of pressure responsive device P¹⁵, and wires 54 and 55 back to battery B. Since valves V² and V³ are both deenergized, main air valves 17 and 18 are both closed, and the supply of fluid pressure to cylinder 9 of motor M from both the high and low pressure distribution systems is therefore cut off; and since valve V¹ is energized, main air valve 16 is open so that cylinder 9 is connected with atmosphere. The braking bars are therefore held in their ineffective or non-braking positions by gravity. Contact 45-45^a of each of the pressure responsive devices P¹⁵, P²⁰⁻³⁰, P⁷⁰⁻⁸⁰ and P^M is closed, while contact 45-45^b of each of the pressure responsive devices P²⁰⁻³⁰, P⁷⁰⁻⁸⁰ and P^M is open.

In explaining the operation of the apparatus as a whole, I will first assume that the operator wishes to make a comparatively light brake application. To do this, he moves lever L from its p¹ position to its p² position, thereby opening contact 50¹ of lever L and closing contact 50². The opening of contact 50¹ of lever L interrupts the circuit which was previously closed for valve V¹ at this contact, and valve V¹ therefore becomes deenergized and disconnects the associated pipe 23 from pipe 24, and connects the associated pipe 23 to atmosphere, thus permitting spring 27 to close valve 16, and hence disconnecting the region of cylinder 9 of motor M between piston 10 and the upper end of the cylinder from atmosphere. The closing of contact 50² of lever L completes a circuit for valve V², and current flows from battery B through wires 73, 64, and 62, contact 50² of lever L, line wire 56, contact 45-45^a of pressure responsive device P²⁰⁻³⁰, wires 57 and 58, winding 21 of valve V², wire 59, and line wire 55 to battery B. Valve V² therefore becomes energized and connects the associated pipe 23 with pipe 24. When the associated pipe 23 becomes connected with pipe 24, fluid pressure is supplied to this pipe 23, and as soon as this pressure increases to 15 pounds per square inch, contact 45-45^a and pressure responsive device P¹⁵ opens. The opening of this contact, under these conditions, however, has no effect on the remainder of the apparatus. The pressure supplied to pipe 23 also causes piston 37 to move downwardly and open valve 17 in the manner previously described, and as was previously pointed out, when valve 17 becomes opened, pipe 16^a becomes connected with pipe 39, so that fluid pressure from the low pressure system is then supplied to the upper end of cylinder 9 of motor M. The fluid pressure thus supplied to cylinder 9 forces piston 10 downwardly and cylinder 9 upwardly, thereby moving the braking bars to their braking positions. As soon as the pressure in cylinder 9 increases to 20 pounds per square inch, contact 45-45^a of pressure responsive device P²⁰⁻³⁰ opens and interrupts the circuit just traced for valve V². Valve V² then becomes deenergized and permits valve 17 to close thus cutting off the supply of fluid pressure to the upper end of cylinder 9 of motor M. Valve V² will then remain deenergized until the pressure of the fluid in cylinder 9 has again decreased to 20 pounds per square inch, whereupon contact 45-45^a of pressure responsive device P²⁰⁻³⁰ will again become closed, which will reestablish the circuit for valve V².

As soon as the pressure in cylinder 9 again reaches 20 pounds per square inch, contact 45-45^a of pressure responsive device P¹⁵ opens and permits valve 17 to close thus cutting off the supply of fluid pressure to the upper end of cylinder 9 of motor M. Valve V² will then remain deenergized until the pressure of the fluid in cylinder 9 has again decreased to 20 pounds per square inch, whereupon contact 45-45^a of pressure responsive device P²⁰⁻³⁰ will again become closed, which will reestablish the circuit for valve V².

V^2 , thus causing fluid to again be supplied to cylinder 9. If the pressure of the fluid in the upper end of cylinder 9 increases to 30 pounds per square inch for any reason, contact 45-45^b of pressure responsive device P^{20-30} will become closed, and will complete another circuit for valve V^1 . This latter circuit passes from battery B through wires 73, 64 and 62, contact 50^c of lever L, line wire 56, contact 45-45^b of pressure responsive device P^{20-30} , wires 60 and 52, winding 21 of valve V^1 , wire 53, contact 45-45^a of pressure responsive device P^{15} , (which contact is now closed due to the fact that valve V^2 is deenergized), and wires 54 and 55 back to battery B. Valve V^1 will therefore now become energized and will cause valve 16 to open, thus venting fluid from cylinder 9. Valve 16 will continue to vent fluid from cylinder 9 until the pressure in cylinder 9 has decreased to 30 pounds per square inch, at which time contact 45-45^b of pressure responsive device P^{20-30} will open and will deenergize valve V^1 . When valve V^1 becomes deenergized, valve 16 will reclose and will prevent further escape of fluid from cylinder 9. It will be seen, therefore, that when lever L occupies its p^2 position, the braking bars will be held in their braking positions by a pressure of between 20 to 30 pounds per square inch.

If the operator desires to make a more powerful brake application, he will move lever L to its p^3 position. This movement of lever L will interrupt all of the previously traced circuits for valves V^1 and V^2 , and will complete another circuit for valve V^2 , which latter circuit passes from battery B, through wires 73 and 64, contact 50^c of lever L, line wire 63, wires 57 and 58, winding 21 of valve V^2 , wire 59, and line wire 55 back to battery B. It will be noted that this latter circuit is controlled solely by contact 50^c of lever L, so that when this circuit becomes closed it will remain closed as long as lever L remains in its p^3 position. When this circuit becomes closed, valve V^2 will of course become energized, thus causing both contact 45-45^a of pressure responsive device P^{15} to open and valve 17 to open. The opening of contact 45-45^a of pressure responsive device P^{15} under these conditions has no effect on the remainder of the apparatus. When valve 17 becomes opened, fluid pressure is admitted to cylinder 9 of motor M from the low pressure distribution system, and since valve V^2 remains energized as long as lever L remains in its p^3 position, it follows that when lever L occupies its p^3 position, the pressure in cylinder 9 of motor M will build up to the full pressure of the low pressure system. When the pressure in cylinder 9 has built up to within five pounds of that in the low pressure system, contact 45-45^a of pressure responsive device P^M will open, but the opening of this contact will likewise have no effect on the remainder of the apparatus as long as lever L remains in its p^3 position.

If a still higher braking force is desired, the operator will move lever L to its p^4 position. When he does this, if the pressure in cylinder 9 of motor M is more than 5 pounds less than the pressure in the low pressure system, so that contact 45-45^a of pressure responsive device P^M is closed, as will be the case if lever L previously occupied its p^1 or p^2 position, valves V^2 and V^3 will become simultaneously energized, the circuit for valve V^2 , under these conditions, passing from battery B through wire 73, contact 50^c of lever L, line wire 65, contact 45-45^a of pressure responsive device P^{70-80} , wire 66, contact 45-45^a

of pressure responsive device P^M , wires 67 and 58, winding 21 of valve V^2 , wire 59, and line wire 55 back to battery B; and the circuit for valve V^3 passing from battery B through wire 73, contact 50^c of lever L, line wire 65, contact 45-45^a of pressure responsive device P^{70-80} , wires 66 and 68, winding 21 of valve V^3 , wires 69 and 53, contact 45-45^a of pressure responsive device P^{15} , wire 54, and line wire 55 back to battery B. The energization of valves V^2 and V^3 will cause fluid pressure to be admitted to the associated cylinders 36 and 41, but before the pressure in these cylinders can build up to a pressure which is sufficient to cause either valve 17 or valve 18 to open, contact 45-45^a of pressure responsive device P^{15} will open, and will interrupt the circuit for valve V^3 , thus deenergizing this valve. It will be seen, therefore, that when lever L is first moved to its p^4 position from its p^1 or p^2 position, valve 17 will open, but valve 18 will remain closed, so that only fluid from the low pressure system will be admitted to cylinder 9. As soon, however, as the pressure in cylinder 9 has built up to within 5 pounds of the pressure in the low pressure system, contact 45-45^a of pressure responsive device P^M will open and will deenergize valve V^2 , thus causing valve 17 to close, and also causing contact 45-45^a of pressure responsive device P^{15} to close. When contact 45-45^a of pressure responsive device P^{15} now becomes closed, it will re-establish the circuit for valve V^3 , and this valve will then become energized and will cause valve 18 to open, thus causing fluid from the high pressure system to be supplied to cylinder 9 of motor M. If, however, when lever L is moved to its p^4 position, the pressure in cylinder 9 of motor M, instead of being more than 5 pounds less than that in the low pressure system as just described, is within 5 pounds of that in the low pressure system, as will be the case if the lever previously occupied its p^3 position, valve V^3 will immediately become energized by virtue of the same circuit which causes this valve to become energized when the lever is moved to its p^4 position from its p^1 or p^2 position, so that under these latter conditions fluid will be immediately supplied to cylinder 9 from the high pressure system. It follows that, when lever L is moved to its p^4 position, if the pressure of the fluid in the motor is more than 5 pounds below that in the low pressure system, fluid will be admitted to the motor from the low pressure system until the pressure in the motor builds up to within 5 pounds of that in the low pressure system, after which fluid will be admitted to the motor from the high pressure system. When lever L occupies its p^4 position, and the pressure in cylinder 9 of motor M has increased to 70 pounds per square inch, contact 45-45^a of the pressure responsive device P^{70-80} will open and will deenergize valve V^3 , and if the pressure increases to 80 pounds per square inch, contact 45-45^b of pressure responsive device P^{70-80} will become closed, and will simultaneously complete circuits for valves V^1 and V^2 . The circuit which is completed for valve V^1 passes from battery B, through wire 73, contact 50^c of lever L, line wire 65, contact 45-45^b of pressure responsive device P^{70-80} , wires 71, 72, 60 and 52, winding 21 of valve V^1 , wire 53, contact 45-45^a of pressure responsive device P^{15} , wire 54, and line wire 55 back to battery B. The circuit which is completed for valve V^2 passes from battery B, through wire 73, contact 50^c of lever L, line wire 65, contact 45-45^b of pressure responsive device P^{70-80} , wire 71, asymmetric U in 73

its low resistance direction, contact 45-45^b of pressure responsive device P^M, wires 67 and 58, winding 21 of valve V², wire 59, and line wire 55 back to battery B. The simultaneous energization of valves V¹ and V² will cause fluid to be simultaneously admitted to the associated cylinders 23 and 36, but before the pressure in cylinder 23 can build up to that at which valve 16 opens, contact 45-45^a of pressure responsive device P¹⁵ will open and will deenergize valve V¹, thus causing fluid which was previously supplied to cylinder 23 to be vented to atmosphere. It will be seen therefore that valve 17 will open, but valve 16 will remain closed. The opening 15 of the valve 17 will connect cylinder 9 of motor M with the low pressure distribution system, and since the pressure in the cylinder is considerably above that in the low pressure system, fluid will be vented into the low pressure system. Fluid 20 will continue to be vented into the low pressure system until the pressure again decreases below 80 pounds per square inch, at which time contact 45-45^b of pressure responsive device P⁷⁰⁻⁸⁰ will open and deenergize valve V², thus causing valve 25 17 to close and disconnect cylinder 9 from the low pressure distribution system.

If the operator moves lever L to its p⁵ position from its p¹ or p² position, when the lever reaches its p⁵ position, contact 45-45^a of pressure responsive device P^M will be closed for reasons which will be apparent from the foregoing description, and under these conditions valves V² and V³ will become simultaneously energized. The circuit for valve V² under these conditions 35 passes from battery B through contact 50^a of lever L, line wire 74, wire 66, contact 45-45^a of pressure responsive device P^M, wires 67 and 58, winding 21 of valve V², wire 59 and line wire 55 back to battery B. The circuit for valve V³ under these conditions passes from battery B through contact 50^b of lever L, line wire 74, wire 68, winding 21 of valve V³, wires 69 and 53, contact 45-45^a of pressure responsive device P¹⁵, wire 54, and line wire 55 back to battery B. As soon as valve V² becomes energized, and the pressure in the associated pipe 23 has built up to 15 pounds per square inch contact 45-45^a of pressure responsive device P¹⁵ will open, and will interrupt the circuit just traced for valve V³ so that this valve will become deenergized. Valve V², however, will remain energized and will cause valve 17 to open, thus causing fluid pressure from the low pressure system to be supplied to cylinder 9 of motor M. When the pressure in cylinder 9 has built up to within 5 pounds of that in the low pressure system, contact 45-45^a of pressure responsive device P^M will open and will deenergize valve V², thus causing valve 17 to close and contact 45-45^a of pressure responsive device P¹⁵ to also close. When valve 17 becomes closed, the supply of fluid pressure to cylinder 9 of motor M from the low pressure system will, of course, be cut off. The closing of contact 45-45^a of pressure responsive device P¹⁵ will re-establish the circuit last traced for valve V³ and this valve will therefore become energized, thus causing valve 18 to open and admit fluid pressure to cylinder 9 of motor M from the low pressure system. Valve V³ will now remain energized as long as the lever remains in its p⁵ position, and it will be apparent, therefore, that the braking bars will continuously exert their maximum braking force under these conditions.

If the operator instead of moving lever L to its p⁵ position from its p¹ or p² position, moves the

lever to its p⁵ position from its p³ or p⁴ position, contact 45-45^a of pressure responsive device P^M will be open when the lever reaches its p⁵ position, and, under these conditions, valve V³ will immediately become energized, so that fluid pressure will immediately be supplied to cylinder 9 of motor M from the high pressure system. 5

I will now assume that the operator has moved lever L to its p⁵ position to cause the braking bars to exert their maximum braking force, and that he wishes to restore the braking bars to their ineffective or non-braking position. To do this, he will move lever L from its p⁵ position to its p¹ position. When he does this, the circuit which was previously closed for valve V³ at contact 50^b of lever L will become interrupted and valve V³ will therefore become deenergized and will disconnect cylinder 9 of motor M from pipe 24, so that the supply of fluid pressure to cylinder 9 from the high pressure system will then be cut off. Furthermore, when the operator moves lever L to its p¹ position, contact 45-45^b of pressure responsive device P^M will be closed since the pressure in the motor cylinder will then be more than 5 pounds greater than that in the low pressure system, and as a result, a circuit will be completed for valve V² which circuit passes from battery B through wires 73, 64, 62 and 61, contact 50^a of lever L, line wire 51, wires 60 and 72, asymmetric unit U in its low resistance direction, contact 45-45^b of pressure responsive device P^M, wires 67 and 58, winding 21 of valve V², wire 59, and line wire 55 back to battery B. A circuit will also be simultaneously closed for valve V¹, which circuit may be traced from battery B through wires 73, 64, 62, and 61, contact 50^b of lever L, line wire 51, wire 52, winding 21 of valve V¹, wire 53, contact 45-45^a of pressure responsive device P¹⁵, wire 54, and line wire 55 back to battery B. Valves V¹ and V² will therefore both become energized. As soon as valve V² becomes energized, however, contact 45-45^a of pressure responsive device P¹⁵ will open, and will interrupt the circuit just traced for valve V¹, thus causing this valve to become immediately deenergized. 45 The energization of valve V² will, of course, cause valve 17 to open, and since the pressure in cylinder 9 of motor M is above that in the low pressure system, fluid from the motor will be vented into the low pressure system. When the pressure in the motor has decreased to within five pounds of that in the low pressure system, contact 45-45^b of pressure responsive device P^M will open and will deenergize valve V², and when valve V² becomes deenergized, valve 17 will close, 50 and contact 45-45^a of pressure responsive device P¹⁵ will also close. The closing of valve 17 will disconnect motor M from the low pressure system, while the closing of contact 45-45^a of pressure responsive device P¹⁵ will re-establish the circuit for valve V¹. Valve V¹ will therefore become energized and will cause valve 16 to open, thus venting the remainder of the fluid in cylinder 9 of motor M to atmosphere. As the fluid in cylinder 9 of motor M is vented to atmosphere, 55 the braking bars will return to their ineffective or non-braking positions by gravity, and when the braking bars have reached their full non-braking positions all parts will be restored to their normal positions in which they are illustrated in the drawings. 60

It will be seen, therefore, that when lever L is moved from its p⁵ position to its p¹ position to restore the braking bars to their non-braking positions, the fluid which was previously supplied to 75

cylinder 9 of motor M will be vented into the low pressure distribution system until the pressure decreases to within 5 pounds of that in the low pressure system after which the remainder of the fluid will be vented to atmosphere, thus effecting a considerable saving in the amount of fluid pressure required over that which would be required if all of the fluid supplied to motor M were vented to atmosphere.

If the operator instead of moving lever L from its p^5 position to its p^1 position, moves the lever from its p^5 position to its p^2 position, valve V^2 will become energized over a circuit which passes from battery B through wires 73, 64 and 62, contact 50² of lever L, line wire 56, contact 45—45^b of pressure responsive device P^{20-30} , wire 72, asymmetric unit U in its low resistance direction, contact 45—45^b of pressure responsive device P^M , wires 67 and 58, winding 21 of valve V^2 , wire 59, and line wire 55 back to battery B. Valve V^1 will also become simultaneously energized over the previously described circuit for this valve including contact 45—45^b of pressure responsive device P^{20-30} . As soon as valve V^2 becomes energized, however, contact 45—45^a of pressure responsive device P^{15} will open and will deenergize valve V^1 . The energization of valve V^2 will of course cause valve 17 to open, and when this valve opens, since the pressure of the fluid in cylinder 9 is then above that in the low pressure system, fluid will be vented from cylinder 9 into the low pressure system. As soon as the pressure in cylinder 9 has decreased to within 5 pounds per square inch of that in the low pressure system, contact 45—45^b of pressure responsive device P^M will open and will deenergize valve V^2 , thus causing valve 17 to close, and contact 45—45^a of pressure responsive device P^{15} to also close. When valve 17 becomes closed, cylinder 9 becomes disconnected from the low pressure system, and when contact 45—45^a of pressure responsive device P^{15} becomes closed, valve V^1 becomes energized and opens valve 16, thus causing fluid to be vented from cylinder 9 to atmosphere. When the pressure of the fluid in cylinder 9 has decreased to 30 pounds per square inch, contact 45—45^b of pressure responsive device P^{20-30} will open, and will deenergize valve V^1 , and the fluid in cylinder 9 will subsequently be maintained at a pressure of between 20 and 30 pounds in the same manner as when lever L is moved to its p^2 position from its p^1 position. It will be seen, therefore, that under the conditions just described, the fluid in cylinder 9 will be vented into the low pressure distribution system until the pressure decreases to substantially the pressure of the low pressure system, after which the fluid in cylinder 9 will be vented to atmosphere, until the pressure decreases to that corresponding to the p^2 position of the lever.

While in the foregoing I have described the operation of the apparatus for only a few of the possible movements of lever L, the operation of the apparatus for the remainder of the movements of lever L is similar to that already described, and it is believed, therefore, that this additional operation will be understood from an inspection of the drawings and from the foregoing without the necessity for describing it in detail here.

One function of the asymmetric unit U is to prevent improper operation of the valves controlled by the pressure responsive device P^M , in the event that the contact points 45^a and 45^b

become short-circuited due to the presence of moisture, or for any other reason.

Referring now to Fig. 2, the apparatus here shown is similar to that shown in Fig. 1, with the exception that the circuits for controlling the valves V have been modified somewhat, and asymmetric units have been employed in some of these circuits, to decrease the number of line wires required between the control point and the car retarder.

The operation of the apparatus shown in Fig. 2 is as follows: When lever L occupies its p^1 or "off" position, valves V^2 and V^3 are both deenergized, and valve V^1 is energized over a circuit which passes from a battery B^1 through line wire 80, wire 81, contact 45—45^a of pressure responsive device P^{15} , wire 82, winding 21 of valve V^1 , wire 83, an asymmetric unit U^2 in its low resistance direction, line wire 84, wire 85, and contact 50¹ of lever L back to battery B. Since valves V^2 and V^3 are deenergized valves 17 and 18 are closed, and the supply of fluid pressure to cylinder 9 of motor M from both the low and high pressure distribution systems is therefore cut off; and since valve V^1 is deenergized, valve 16 is open, so that cylinder 9 of motor M is connected to atmosphere. The braking bars are therefore held in their non-braking positions by gravity.

If, now, lever L is moved to its p^2 position, valve V^1 will become deenergized, and valve V^2 will become energized over a circuit which passes from battery B^1 through line wire 80, wire 86, winding 21 of valve V^2 , contact 45—45^a of pressure responsive device P^{20-30} , line wire 87, and contact 50² of lever L back to battery B^1 . The deenergization of valve V^1 will cause valve 16 to close and disconnect cylinder 9 of motor M from atmosphere, while the energization of valve V^2 will cause valve 17 to open and connect cylinder 9 with pipe 39, so that fluid pressure will then be supplied to cylinder 9 from the low pressure distribution system, thus causing the braking bars to move to their braking positions. When the pressure of the fluid in cylinder 9 increases to 20 pounds per square inch, contact 45—45^a of pressure responsive device P^{20-30} will open and will deenergize valve V^2 , thus causing valve 17 to close and disconnect cylinder 9 from the low pressure distribution system; and if the pressure of the fluid in cylinder 9 increases to 30 pounds per square inch, contact 45—45^b of pressure responsive device P^{20-30} will become closed, and will complete another circuit for valve V^1 , which latter circuit passes from battery B^1 , through line wire 80, wire 81, contact 45—45^a of pressure responsive device P^{15} , wire 82, winding 21 of valve V^1 , wire 83, asymmetric unit U^3 in its low resistance direction, contact 45—45^b of pressure responsive device P^{20-30} , line wire 87, and contact 50² of lever L back to battery B^1 . Valve V^1 will therefore become energized and will cause valve 16 to open, so that fluid will then be vented to atmosphere. Valve 16 will continue to vent fluid from cylinder 9 to atmosphere until the pressure in the cylinder again decreases to 30 pounds per square inch, at which time contact 45—45^b of pressure responsive device P^{20-30} will open and will deenergize valve V^1 , thus causing valve 16 to close.

It will be seen, therefore, that with the apparatus shown in Fig. 2, when lever L is moved to its p^2 position, the braking bars will be held in their braking positions by a pressure of between 20 to 30 pounds per square inch in the same manner as with the apparatus shown in Fig. 1.

If lever L is moved from its p^2 position to its p^3

position, the circuit last traced for valve V² will become interrupted, and another circuit for valve V² will become closed. This latter circuit passes from a battery B² through contact 50³ of lever L, line wire 84, asymmetric unit U¹ in its low resistance direction, wires 88 and 89, winding 21 of valve V², wire 86, and line wire 89 back to battery B². The energization of valve V² by virtue of the circuit just traced will of course cause valve 17 to open and admit fluid to cylinder 9 of motor M from the low pressure distribution system. It will be noted that the circuit over which valve V² is energized under these conditions is controlled entirely by contact 50³ of lever L, and it follows therefore that valve V² will now remain energized as long as lever L remains in its p³ position, and the braking bars will therefore be held in their braking positions under these conditions by fluid at the full pressure of the low pressure distribution system. It should be pointed out that when the pressure of the fluid in cylinder 9 increases to within five pounds of that in the low pressure system, contact 45—45^a of pressure responsive device P^M will open, but the opening of this contact will have no effect on the remainder of the apparatus as long as lever L remains in its p³ position.

I will next assume that lever L is moved from its p³ position to its p⁴ position. Under these conditions valve V² will become deenergized and valve V³ will become energized, thus causing fluid pressure to be supplied to the upper end of cylinder 9 from the high pressure system. The circuit over which valve V³ becomes energized under these conditions passes from battery B¹, through line wire 80, wire 81, contact 45—45^a of pressure responsive device P¹⁵, wires 82 and 90, winding 21 of valve V³, wires 91 and 92, contact 45—45^a of pressure responsive device P^{70—80}, line wire 93, contact 50⁴ of lever L, and wire 94 back to battery B¹. When the pressure of the fluid in the upper end of cylinder 9 becomes more than five pounds greater than that in the low pressure distribution system, contact 45—45^b of pressure responsive device P^M will close, but the closing of this contact under these conditions will have no effect on the remainder of the apparatus. When the pressure in the upper end of cylinder 9 increases to 70 pounds per square inch, contact 45—45^a of pressure responsive device P^{70—80} will open and will deenergize valve V³, thus causing the supply of fluid pressure to cylinder 9 from the high pressure distribution system to be cut off. If the pressure in the upper end of cylinder 9 increases to 80 pounds per square inch for any reason, contact 45—45^b of pressure responsive device P^{70—80} will close, and will simultaneously complete circuits for valves V¹ and V². The circuit which is completed for valve V¹ passes from battery B¹ through line wire 80, wire 81, contact 45—45^a of pressure responsive device P¹⁵, wire 82, winding 21 of valve V¹, wire 83, asymmetric unit U³ in its low resistance direction, contact 45—45^b of pressure responsive device P^{70—80}, line wire 93, contact 50⁴ of lever L, and wire 94 back to battery B¹. The circuit which is completed for valve V² passes from battery B¹ through line wire 80, wire 86, winding 21 of valve V², wires 89, 88 and 95, contact 45—45^b of pressure responsive device P^M, asymmetric unit U³ in its low resistance direction, contact 45—45^b of pressure responsive device P^{70—80}, line wire 93, contact 50⁴ of lever L, and wire 94 back to battery B¹. The simultaneous energization of valves V¹ and V² will cause fluid pressure to be simultaneously supplied to cylinders 28 and 36, but before the pressure in cylinder

28 can build up sufficiently to cause valve 16 to open contact 45—45^a of pressure responsive device P¹⁵ will open and will interrupt the circuit which was previously closed for valve V¹, thus cutting off the supply of fluid pressure to cylinder 28. Valve 17, however, will open and will connect cylinder 9 with the low pressure distribution system, and since the pressure in cylinder 9 is then above that in the low pressure system fluid will be vented into the low pressure system. Fluid will continue to be vented into the low pressure system until the pressure again decreases below 80 pounds per square inch, at which time contact 45—45^b of pressure responsive device P^{70—80} will open and will deenergize valve V², thus causing valve 17 to reclose and disconnect cylinder 9 from the low pressure system.

If lever L, instead of being moved to its p⁴ position from its p³ position, is moved to its p⁴ position directly from its p¹ or p² position, contact 45—45^a of pressure responsive device P^M will be closed when the lever L reaches its p⁴ position, and under these conditions valve V³ will become energized over the circuit previously traced, and valve V² will also become energized over a circuit which passes from battery B¹, through line wire 80, wire 86, winding 21 of valve V², wires 89, 88 and 95, contact 45—45^a of pressure responsive device P^M, wires 96 and 92, contact 45—45^a of pressure responsive device P^{70—80}, line wire 93, contact 50⁴ of lever L, and wire 94 back to battery B¹. As soon as valve V² becomes energized, however, contact 45—45^a of pressure responsive device P¹⁵ will open and will deenergize valve V³ so that only valve V² will remain energized. The energization of valve V² will cause fluid pressure to be supplied to cylinder 9 of motor M from the low pressure system until the pressure increases to within five pounds of that in the low pressure system, at which time contact 45—45^a of pressure responsive device P^M will open and will deenergize valve V², thus causing the supply of fluid pressure to cylinder 9 from the low pressure system to be cut off. As soon as valve V² becomes deenergized contact 45—45^a of pressure responsive device P¹⁵ will close, and when this contact becomes closed, the circuit which was previously closed for valve V³ will be re-established, and the operation of the apparatus from this point on will be the same as was previously described when lever L was moved from its p³ position to its p⁴ position.

If lever L is moved to its p³ position or its p⁴ position long enough to permit the pressure in the upper end of cylinder 9 of motor M to build up to the pressure at which contact 45—45^a of pressure responsive device P^M opens, and the lever is then moved to its p⁵ position, valve V³ will immediately become energized and will subsequently remain energized as long as the lever remains in its p⁵ position by virtue of a circuit which passes from battery B² through contact 50⁵ of lever L, line wire 93, an asymmetric unit U⁴ in its lower resistance direction, wire 91, winding 21 of valve V³, wires 90 and 82, contact 45—45^a of pressure responsive device P¹⁵, wire 81, and line wire 80 back to battery B². When valve V³ becomes energized, fluid pressure will, of course, be supplied to cylinder 9 of motor M from the high pressure distribution system, and it will be apparent, therefore, that under these conditions motor M will be constantly supplied with fluid pressure from the high pressure system as long as the lever remains in its p⁵ position. If, however, lever L instead of being moved

to its p^5 position from its p^3 or p^4 position in the manner just described is moved to its p^5 position directly from its p^1 or p^2 position, so that contact 45-45^a of pressure responsive device P^M is still closed when the lever reaches its p^5 position, valve V³ will become energized over the circuit last traced for this valve, and valve V² will simultaneously become energized over a circuit which passes from battery B² through contact 50^b of lever L, line wire 93, asymmetric unit U⁴ in its lower resistance direction, wire 96, contact 45-45^a of pressure responsive device P^M, wires 95, 88 and 89, winding 21 of valve V², wire 86, and line wire 80 back to battery B². The energization of valve V² will cause contact 45-45^a of pressure responsive device P¹⁵ to open before valve 18 opens, and when contact 45-45^a of pressure responsive device P¹⁵ opens, the circuit over which valve V³ was previously energized will be come interrupted, thus deenergizing this valve. Valve V², however, will remain energized and will cause valve 17 to open and admit fluid pressure to cylinder 9 of motor M from the low pressure distribution system until the pressure in the motor increases to within five pounds of that in the low pressure system, at which time contact 45-45^a of pressure responsive device P^M will open and will deenergize valve V². The deenergization of valve V² will, of course, cause the further supply of fluid pressure to cylinder 9 of motor M from the low pressure distribution system to be cut off, and will also cause contact 45-45^a of pressure responsive device P¹⁵ to close. As soon as contact 45-45^a of pressure responsive device P¹⁵ becomes closed, the circuit over which valve V³ was previously energized will become re-established, and the operation of the apparatus will then be the same as when lever L is moved to its p^5 position from its p^3 or p^4 position. As soon as the pressure in cylinder 9 of motor M has reached a value which is more than five pounds greater than that in the low pressure system, contact 45-45^b of pressure responsive device P^M will close, but the closing of this contact under these conditions will have no effect on the remainder of the apparatus as long as the lever remains in its p^5 position.

If, after lever L has been moved to its p^5 position, the lever is moved to its p^2 position, valve V³ will become deenergized and valves V² and V¹ will simultaneously become energized. The circuit over which valve V² becomes energized under these conditions passes from battery B¹ through line wire 80, wire 86, winding 21 of valve V², wires 89, 88 and 95, contact 45-45^b of pressure responsive device P^M, asymmetric unit U³ in its low resistance direction, contact 45-45^b of pressure responsive device P²⁰⁻³⁰, line wire 87, and contact 50^b of lever L back to battery B¹. The circuit over which valve V¹ becomes energized under these conditions is the same as the circuit over which this valve becomes energized when lever L is moved to its p^2 position from its p^1 position, and the pressure in cylinder 9 of motor M increases to more than 30 pounds per square inch. The energization of valve V² under these conditions will cause contact 45-45^a of pressure responsive device P¹⁵ to open, and as soon as this contact opens, the circuit over which valve V¹ was previously energized will become interrupted so that valve V¹ will immediately become deenergized. The energization of valve V² will also cause valve 17 to open, and since the pressure of the fluid in cylinder 9 of motor M is now above that in the low pressure distribution sys-

tem, fluid will be vented from cylinder 9 into the low pressure distribution system. When the pressure in cylinder 9 of motor M decreases to within five pounds of that in the low pressure distribution system, contact 45-45^b of pressure responsive device P^M will open and will de-energize valve V², thus causing valve 17 to close and disconnect cylinder 9 from the low pressure distribution system. The deenergization of valve V² will also cause contact 45-45^a of pressure responsive device P¹⁵ to close and the closing of this contact, in turn, will re-establish the circuit for valve V¹, thus causing valve 16 to open and vent fluid from cylinder 9 to atmosphere. When the pressure in cylinder 9 has decreased to 30 pounds per square inch contact 45-45^b of pressure responsive device P²⁰⁻³⁰ will open and will deenergize valve V¹, and the pressure of the fluid in cylinder 9 of motor M will then be maintained at a value of between 20 and 30 pounds per square inch in the same manner as when lever L is moved to its p^2 position from its p^1 position.

I will now assume that lever L occupies its p^5 position, and that the operator moves the lever directly to its p^1 position. Under these conditions, when the lever reaches its p^1 position, contact 45-45^b of pressure responsive device P^M will be closed, and a circuit will therefore be completed for valve V² which may be traced from battery B¹ through line wire 80, wire 86, winding 21 of valve V², wires 89, 88 and 95, contact 45-45^b of pressure responsive device P^M, asymmetric unit U² in its low resistance direction, line wire 84, wire 85, and contact 50^b of lever L back to battery B¹. The circuit previously traced for valve V¹ including contact 50^b of lever L will also become simultaneously closed under these conditions, but as soon as valve V² becomes energized, the resultant opening of contact 45-45^a of pressure responsive device P¹⁵ will interrupt this circuit for valve V¹, and valve V¹ will therefore immediately become deenergized. The energization of valve V² will cause cylinder 9 of motor M to become connected with the low pressure distribution system, and fluid will therefore be vented into the low pressure distribution system until the pressure in the motor decreases to within five pounds of that in the low pressure system, at which time contact 45-45^b of pressure responsive device P^M will open and will deenergize valve V². When valve V² becomes deenergized, valve 17 will close and will disconnect cylinder 9 from the low pressure system. Furthermore, when valve V² becomes closed, contact 45-45^a of pressure responsive device P¹⁵ will close, and will re-establish the circuit for valve V¹. Valve V¹ will therefore become energized and will cause valve 16 to open, thus venting the remainder of the fluid in cylinder 9 to atmosphere. As the pressure in the upper end of cylinder 9 decreases, the braking bars will return to their non-braking positions by gravity, and when the braking bars reach their non-braking positions, all parts will be restored to their normal positions in which they are shown in the drawings.

Referring now to Fig. 3, the apparatus here shown is similar to that shown in Fig. 1 with the exception that the pressure responsive device P¹⁵ has been replaced by a relay A which is connected in multiple with the winding 21 of valve V², and which therefore becomes energized whenever the valve V² becomes energized. Relay A is provided with a contact 100 which opens whenever this relay becomes energized, and this contact performs the same functions which the 75

contact 45—45^a of the pressure responsive device P¹⁵ shown in Fig. 1 performs.

The operation of the apparatus shown in Fig. 3 is similar to that shown in Fig. 1, and it is believed that this operation will be readily understood from the foregoing description, and from an inspection of the drawings, without describing it in detail.

Referring now to Fig. 4, the portion of the apparatus here shown is likewise similar to the corresponding portion of the apparatus shown in Fig. 1, with the exception that the pressure responsive device P¹⁵ has again been eliminated, and a contact 101 has been provided which contact is mechanically connected to the armature 22 of valve V² in such manner that this contact will be closed or opened according as valve V² is deenergized or energized. The contact 101 performs the same functions as the contact 45—45^a of the pressure responsive device P¹⁵ shown in Fig. 1 and the operation of the apparatus shown in Fig. 4 is similar in all respects to that shown in Fig. 1.

It should be noted that while I have shown the relay A in Fig. 3, and the contact 101 in Fig. 4 associated with a circuit arrangement for controlling the valves V similar to that shown in Fig. 1, these parts could equally well be used in connection with the circuit arrangement shown in Fig. 2 for controlling these valves, and similar operation of the apparatus in both cases would result.

Although I have herein shown and described only a few forms of railway braking apparatus embodying my invention, it is understood that various changes and modifications may be made therein within the scope of the appended claims without departing from the spirit and scope of my invention.

Having thus described my invention, what I claim is:

1. Railway braking apparatus comprising a braking bar extending parallel to a track rail, a fluid pressure motor for moving said braking bar toward said track rail to a braking position, a first pipe connected with a source of relatively low pressure fluid, a second pipe constantly connected with a source of relatively high pressure fluid, two pressure responsive devices, one subjected to the pressure of the fluid in said first pipe and the other subjected to the pressure of the fluid in said motor, a contact controlled jointly by said two devices in such manner that said contact will be closed when the pressure in said motor is below a predetermined pressure which is less than the pressure in said first pipe and will be open at all other times, and means controlled by said contact for connecting said motor with said first or said second pipe.

2. Railway braking apparatus comprising a braking bar extending parallel to a track rail, a fluid pressure motor for moving said braking bar toward said track rail to braking positions, a first pipe connected with a source of relatively low pressure fluid, a second pipe connected with a source of relatively high pressure fluid, two pressure responsive devices one subjected to the pressure of the fluid in said first pipe and the other subjected to the pressure of the fluid in said motor, two magnet valves, means controlled by the one valve for connecting said first pipe with said motor, means controlled by the other valve for connecting said second pipe with said motor, a contact controlled jointly by said two devices in such manner that said contact will be closed

when the pressure in said motor is below a predetermined pressure which is less than the pressure in said first pipe and will be open at all other times, and means controlled by said contact for selectively controlling said two valves. 5

3. Railway braking apparatus comprising a braking bar extending parallel to a track rail, a fluid pressure motor for moving said braking bar toward said track rail to a braking position, a first pipe connected with a source of relatively low pressure fluid, a second pipe connected with a source of relatively high pressure fluid, two pressure responsive devices one subjected to the pressure of the fluid in said first pipe and the other subjected to the pressure of the fluid in said second pipe, a first contact controlled jointly by said two devices in such manner that said contact will be closed when the pressure in said motor is below a predetermined pressure which is less than the pressure in said first pipe and open at all other times, a first magnet valve effective when energized for connecting said first pipe with said motor, a second magnet valve effective when energized for connecting said second pipe with said motor, a second contact which is closed or open according as said first valve is deenergized or energized, means controlled by said first contact for controlling said first magnet valve, and means controlled by said second contact for controlling said second magnet valve. 30

4. Railway braking apparatus comprising a braking bar extending parallel to a track rail, a fluid pressure motor for moving said braking bar toward said track rail to a braking position, a first pipe connected with a source of relatively low pressure fluid, a second pipe connected with a source of relatively high pressure fluid, two Bourdon tubes one subjected to the pressure of the fluid in said first pipe and the other subjected to the pressure of the fluid in said motor, 40 said tubes being mechanically connected together in such manner that when pressure is supplied to said tubes they will exert opposing forces on the connecting member, a contact controlled by said two Bourdon tubes in such manner that said contact will be closed when and only when the pressure in said motor is below a predetermined pressure which is less than the pressure in said first pipe, a first magnet valve, means controlled by said first magnet valve for connecting said first pipe with said motor, a second magnet valve, means controlled by said second magnet valve for connecting said second pipe with said motor, a second contact which becomes opened whenever said first valve becomes energized, means 50 controlled by said first contact for controlling said first magnet valve, and means controlled by said second contact for at times controlling said second magnet valve.

5. Railway braking apparatus comprising a braking bar extending parallel to a track rail, a fluid pressure motor for moving said braking bar toward said track rail to a braking position, a first pipe connected with a source of relatively low pressure fluid, a second pipe connected with a source of relatively high pressure fluid, a first Bourdon tube connected to said first pipe through a reservoir and a restricted orifice, whereby said first tube is subjected to the pressure in said first pipe but not to sudden variations in the pressure in said first pipe, a second Bourdon tube subjected to the pressure in said motor, means for mechanically connecting said Bourdon tubes together in such manner that when said tubes are both subjected to fluid pressure they will exert opposing 70

75

forces on the connecting member, a contact controlled by said tubes in such manner that said contact will be closed when and only when the pressure in said motor is below a predetermined pressure which is less than the pressure in said first pipe, and means controlled by said contact for selectively connecting said pipes with said motor.

6. Railway braking apparatus comprising a braking bar extending parallel to a track rail, a fluid pressure motor for moving said braking bar toward said track rail to a braking position, a first pipe connected with a source of relatively low pressure fluid, a second pipe connected with a source of relatively high pressure fluid, two Bourdon tubes one subjected to the pressure of the fluid in said first pipe and the other subjected to the pressure of the fluid in said motor, said tubes being mechanically connected together in such manner that when pressure is supplied to said tubes they will exert opposing forces on the connecting member, a first contact controlled by said two Bourdon tubes in such manner that said first contact will be closed when and only when the pressure in said motor is below a predetermined pressure which is less than the pressure in said first pipe, a first magnet valve, means controlled by said first contact for at times energizing said first magnet valve, means effective when said first magnet valve is energized for connecting said motor with said first pipe, a third Bourdon tube subjected to the pressure in said second pipe when said first magnet valve becomes energized, a second contact controlled by said third Bourdon tube and arranged to become opened when said third tube becomes subjected to the pressure in said second pipe, a second magnet valve, means for at times energizing said second magnet valve when said second contact is closed, and means effective when said second magnet valve becomes energized for connecting said motor with said second pipe.

7. Railway braking apparatus comprising a braking bar extending parallel to a track rail, a fluid pressure motor for moving said braking bar toward said track rail to a braking position, a first pipe connected with a source of relatively low pressure fluid, a second pipe connected with a source of relatively high pressure fluid, two Bourdon tubes one subjected to the pressure of the fluid in said first pipe and the other subjected to the pressure of the fluid in said motor, said tubes being mechanically connected together in such manner that when pressure is supplied to said tubes they will exert opposing forces on the connecting member, a first contact controlled by said two Bourdon tubes in such manner that said first contact will be closed when and only when the pressure in said motor is below a predetermined pressure which is less than the pressure in said first pipe, a first magnet valve, means controlled by said first contact for at times energizing said first magnet valve, means effective when said first magnet valve is energized for connecting said motor with said first pipe, a third Bourdon tube subjected to the pressure in said second pipe when said first magnet valve becomes energized, a second contact controlled by said third Bourdon tube and arranged to become opened when said third tube becomes subjected to the pressure in said second pipe, a second magnet valve, means for at times energizing said second magnet valve when said second contact is closed, and means effective when said second magnet valve becomes energized for connecting said motor with said second pipe.

becomes energized for connecting said motor with said second pipe, a third contact controlled by said two Bourdon tubes which are connected together and arranged to become closed when and only when the pressure in said motor is above a predetermined pressure which is greater than the pressure in said first pipe, and means controlled by said third contact for at times energizing said first magnet valve.

8. Railway braking apparatus comprising a braking bar extending parallel to a track rail, a fluid pressure motor for moving said braking bar toward said track rail to a braking position, a first pipe connected with a source of relatively low pressure fluid, a second pipe connected with a source of relatively high pressure fluid, two Bourdon tubes one subjected to the pressure of the fluid in said first pipe and the other subjected to the pressure of the fluid in said motor, said tubes being mechanically connected together in such manner that when pressure is supplied to said tubes they will exert opposing forces on the connecting member, a first contact controlled by said two Bourdon tubes in such manner that said first contact will be closed when and only when the pressure in said motor is below a predetermined pressure which is less than the pressure in said first pipe, a first magnet valve, means controlled by said first contact for at times energizing said first magnet valve, means effective when said first magnet valve is energized for connecting said motor with said first pipe, a relay connected in multiple with said first magnet valve and provided with a contact which becomes open when said relay becomes energized, a second magnet valve, means for at times energizing said second magnet valve when the contact of said relay is closed, and means effective when said magnet valve becomes energized for connecting said motor with said second pipe.

9. Railway braking apparatus comprising a braking bar extending parallel to a track rail, a fluid pressure motor for moving said braking bar toward said track rail to a braking position, a first pipe connected with a source of relatively low pressure fluid, a second pipe connected with a source of relatively high pressure fluid, two Bourdon tubes one subjected to the pressure of the fluid in said first pipe and the other subjected to the pressure of the fluid in said motor, said tubes being mechanically connected together in such manner that when pressure is supplied to said tubes they will exert opposing forces on the connecting member, a first contact controlled by said two Bourdon tubes in such manner that said first contact will be closed when and only when the pressure in said motor is below a predetermined pressure which is less than the pressure in said first pipe, a first magnet valve, means controlled by said first contact for at times energizing said first magnet valve, means effective when said first magnet valve is energized for connecting said motor with said first pipe, a second contact mechanically connected with the movable element of said first magnet valve in such manner that said second contact will become opened when said first magnet valve becomes energized, a second magnet valve, means for at times energizing said second magnet valve when said second contact is closed, and means effective when said second magnet valve becomes energized for connecting said motor with said second pipe.

HERBERT L. BONE.
